APPARATUS FOR HANDLING BRICKS

Application filed July 5, 1928. Serial No. 290,651.

The present invention relates primarily to the handling and shipping of expensive bricks such as are used for facing purposes in building structures. Great care is required in the handling of such bricks to avoid breaking, chipping or otherwise marring them. The handling methods practiced heretofore require much slow and tedious manual labor, which adds materially to the cost of the bricks and often fails to prevent damage to a large percentage of them. There are also serious faults in the shipping methods practiced. Owing to the manner of storing the bricks upon a car the latter can be loaded to less than half of its capacity. If the car is loaded beyond a certain degree the mass of bricks, due to its inertia, will surge when the car is suddenly started or stopped and often cause serious damage to both the car and the bricks. The waste of car space consequent to keeping the lading down to a safe limit adds greatly to the cost of transportation.

The invention contemplates the use of a strong base or pallet on which the desired number of bricks are stacked. An enclosing or surrounding cage or casing is dropped down over the stack and detachably locked to the pallet. A hoisting mechanism is provided, having detachable means for connection with the casing or cage, so that the pallet, the casing and the hoisting mechanism may be detachably connected together, for the hoisting and lowering operations. The hoisting mechanism may be detached from the casing so that the casing will remain locked to the pallet and enclosing the bricks. By the manipulation of suitable devices attached to the hoisting mechanism the casing may be locked or unlocked from the pallet. Such a mechanism provides a very flexible apparatus for use in stacking the bricks in railway cars or automobile trucks for transportation with the enclosing cage attached; provides a convenient and safe means by which expensive facing bricks may be stacked in the retail yards with or without the enclosing cage; and provides an economical and safe means by which the stacked bricks may be taken from the

stacks in the retail yards, placed in trucks and transported to the job without any danger of defacing the bricks and without the necessity of counting the bricks after they have been once stacked on the pallet at the brickyard or place of manufacture.

In the drawings:

Fig. 1 is a perspective view of my apparatus assembled and suspended for conveying a stack of bricks;

Fig. 2 a side elevation of the apparatus partly in section;

Fig. 3 an end elevation of the apparatus;

Fig. 4 a vertical section taken on the line 4—4 of Fig. 3 showing the lower hooks swung outward to release the pallet;

Fig. 5 a vertical section taken on the line 5—5 of Fig. 3 showing the casing lifted from the pallet;

Fig. 6 a section taken on the line 6—6 of Fig. 3 showing the upper hooks swung outward to release the casing from the hoisting head;

Fig. 7 a miniature side view of several superposed shipping units each comprising a pallet, a stack of bricks and a casing;

Fig. 8 a similar view of a pallet supporting a stack of bricks; and

Figs. 9 and 10 detail sectional views showing a locking means to prevent accidental release of the lower hooks.

The apparatus includes a brick-supporting pallet 1 formed of stout wooden bars 2 all of the same size and form, arranged parallel, and laterally spaced apart. Spacing blocks 3 are interposed between the ends of the bars and are secured in place in any suitable manner to hold the bars spaced and form a strong rigid pallet unit. The bars are rectangular in cross section and their upper sides are disposed in the same plane to form a flat support for a stack of bricks. The spacing blocks adjacent the four corners of the pallet are spaced inwardly from the ends of the latter to provide four recesses 4. Two rods 5 at opposite ends of the pallet extend through registering apertures in the remaining blocks and in the ends of the bars 2 and across the recesses 4. The portions of said rod exposed within the recesses form four

100

keepers 6 adjacent the corners of the pallet to be engaged by lifting means, as will be described later in the specification.

5 A casing or cage 7 is provided for surrounding a stack of bricks upon the pallet and preventing their displacement. The casing is of box-like form and is open at top and bottom to permit it to be lowered around a stack of bricks and allow the top 70 of the stack to protrude. When the casing is properly positioned upon the pallet its lower side edges rest upon the outermost pallet bars 2 and its lower end edges rest upon the bars 2 and the intermediate spacing bars 3 adjacent the inner ends of the latter. The casing is preferably formed of metal and is provided at each end with three vertical channel irons 8 rigidly secured to the casing in any suitable manner and disposed, two adjacent the corners of the casing, and the remaining one at the center. These channel irons 8 extend the entire height of the casing, and each of the side irons is provided adjacent its end with a short keeper bar 9 which extends across the channel and is secured in apertures at the channel sides. Two rock shafts 10 are disposed transversely at opposite ends of the casing and are rockably supported in apertures 11 formed in the sides of the channel irons 8, adjacent the lower ends thereof. Each shaft extends across its supporting channel irons, and fixed to the end portions of the shaft, which extend across the side channel irons, are two depending hooks 12 which 85 open inwardly. When the cage is disposed upon the pallet, the lower ends of the side channels open directly into the pallet recesses 4 and the hooks 12 are adapted to engage the keepers 6 of the pallet to anchor the casing thereto. A short crank 13 is fixed to the intermediate portion of each shaft 10, extends forwardly from it and is disposed within the central channel iron. Pivoted to the outer end of the crank 13 and extending upward within the channel iron is a link 14. The link terminates below the upper end of the channel iron and is formed with a head 15. A pin 16 is carried by the head 15 and has projecting ends which extend into vertical slots 17 in the opposite sides of the channel iron. A lug 18 is formed upon the head and extends outward from the pin. These parts form part of an operative connection for the shaft 10 and the hooks 12.

60 The cage and the pallet, with a stack of bricks thereon, are adapted to be lifted and conveyed by a hoisting head 19. This head includes a central beam 20 and a pair of transverse end beams 21 rigidly carried by the central beam. In the drawings the head is represented in the form of a single casting. However, it may be constructed of assembled sections. Midway between its ends the central beam is formed with a loop or eye 22

to which a hoisting chain or cable may be attached for suspending the head. Each beam 21 is formed at its ends with pairs of spaced ears 23 and at its center with a pair of ears 24. These ears 23 and 24 all extend 75 outward and are so disposed that when the hoisting head is located directly over the casing 7 they will be in direct vertical alignment with the channel irons 8 carried by the cage. The ears form supports for two shafts 75 25 at opposite ends of the hoisting head, each shaft being rotatably mounted in apertures 26 formed in the ears and extending across the spaces between the latter. Fixed to the shaft 25 between each pair of ears 23 is a 80 depending hook 27 which opens inwardly. These four hooks extend materially below the beams 21 and are adapted to enter the upper ends of the side channel irons 8 and engage the keepers 9 for lifting the cage. 85

Each shaft 25 has a short, upwardly extending crank arm 28 fixed to it at one side of the central ears 24, and pivotally connected to each crank arm 28 is a reach rod 29 which extends inwardly along the central beam 20 90 and is slideable through a guide 30 upon said beam. The inner ends of the rods 29 terminate at points within convenient reach of an operator stationed at the suspension point of the hoisting head. Reciprocation of the 95 reach rods causes the shafts 25 and their attached hooks 27 to be rocked. An outward movement of the rods rocks the hooks inward for engagement with the keepers 9 and an inward movement of the rods cause a release of the hooks from the keepers.

At opposite ends of the hoisting head are two comparatively large, depending hook members 32 forming part of the means for operating the lower hooks 12. Each hook member 32 has an elongated shank disposed between the ears 24 and formed intermediate its ends with an elongated slot 33 through which the shaft 25 extends. This mounts the hook member upon the shaft for both pivotal and sliding movement. The lower end of the member 32 forms the hook and has a notch 34 to receive the lug 18 of one of the link heads 15 and effect a detachable operative connection with it. The end of the hook and the entrance to the notch are rounded to facilitate the engagement of the hook with the lug 18. The beam 20 of the hoisting head is formed with two slots 35 adjacent the end beams 21, and fulcrumed in said slots are two bell-crank levers 36. The fulcrum of each lever comprises a pin 37 whose ends project beyond the opposite sides of the lever and into elongated slots 38 formed in the beam 20 and extending longitudinally thereof. This 110 mounts the lever upon the beam for both rocking and sliding movements. Each lever is formed with an arm 39 extending from its fulcrum outwardly and upwardly to the upper end of the adjacent hook 32 and piv- 115

totally connected thereto as at 40, and an arm 41 extending inwardly and upwardly toward the suspension point of the hoisting head. At their inner ends the arms 40 of the two levers are provided with handles 42 also within convenient reach of the operator at the suspension point. By sliding the levers 36 at their fulcrums the hooks 32 are rocked about the shafts 25 to grapple with the link heads 32 and grapple for the lugs 18 of the link heads 15. When operative connections have been made between said hooks and lugs the handles 42 are raised to swing the levers about their fulcrums 37 and depress the hooks 32. This movement of the hooks slides the link heads 15 downward at their pin and slot connections with the channel irons and shifts the links 14 and the cranks 13, to rock the shafts 10 and swing the lower hooks 12 inward against the keepers 6 of the pallet, as shown in Fig. 2. Strong, positive lifting connections are now established between the hoisting head 19 and the pallet 1 by means of the hooks 27, the keepers 9, the side channel irons 8, the hooks 12 and the keepers 6, so that the pallet and bricks may be safely lifted and conveyed. The lower hooks 12 are sufficiently elongated to provide clearance for grappling the keepers 6, and when the pallet is lifted there will be slight separation between the casing and the pallet. The casing is thus permitted to ride upward and better surround and support the top layer of bricks. When the weight is resting upon the hooks 12 and the latter are thereby held against release, the hooks 32 may be safely swung out of engagement with the lugs 18 by grasping the handles 42 and sliding the levers 36 inwardly.

In the use of my apparatus a stack of bricks of a certain number is first built up upon the pallet 1 as shown in Fig. 8. In practice I have found that a stack of five hundred bricks forms a most desirable unit for handling and shipping, and the pallet 1 and cage 7 have been proportioned to accommodate a stack of that size. However these proportions may be varied. A plurality of units comprising the stacked bricks and their supporting pallets may be built up in superposed relation at the brickyard until it is required to remove them. When a unit is to be removed and shipped the first step is to pick up a casing 7 and lower it around the stack of bricks by means of the hoisting head 19. The latter will be suspended from the chain or cable of a power-operated hoisting apparatus. Preferably a seat for an operator will be provided either upon the hoisting head or upon its suspension means, and suitable electric control means will be provided adjacent said seat to enable the operator to control the raising and lowering of the hoisting means and the lateral movements thereof. This seat and control means form no part of the present application and they have been omitted in order to simplify the showing.

A lifting connection between the hoisting head and the casing 7 is effected by lowering the head to a position directly over the casing and operating the reach rods 29 to swing the hooks 27 and grapple for the keepers 9. When the hooks are engaged with the keepers the casing is carried by the hoisting head to a position over one of the stacked units and lowered upon the pallet 1 thereon to surround the stack of bricks. The height of the casing is slightly less than that of the stack so that the latter projects above the casing, for a purpose which will appear presently. Also the hooks 27 are sufficiently elongated to provide a good clearance between the bricks and the hoisting head.

Having lowered the casing 7 upon the pallet, lifting connections therebetween are next made by grasping the handles 42 and sliding the levers 36 to rock the large central hooks

32 and grapple for the lugs 18 of the link heads 15. When operative connections have been made between said hooks and lugs the handles 42 are raised to swing the levers about their fulcrums 37 and depress the hooks 32. This movement of the hooks slides the link heads 15 downward at their pin and slot connections with the channel irons and shifts the links 14 and the cranks 13, to rock the shafts 10 and swing the lower hooks 12 inward against the keepers 6 of the pallet, as shown in Fig. 2. Strong, positive lifting connections are now established between the hoisting head 19 and the pallet 1 by means of the hooks 27, the keepers 9, the side channel irons 8, the hooks 12 and the keepers 6, so that the pallet and bricks may be safely lifted and conveyed. The lower hooks 12 are sufficiently elongated to provide clearance for grappling the keepers 6, and when the pallet is lifted there will be slight separation between the casing and the pallet. The casing is thus permitted to ride upward and better surround and support the top layer of bricks. When the weight is resting upon the hooks 12 and the latter are thereby held against release, the hooks 32 may be safely swung out of engagement with the lugs 18 by grasping the handles 42 and sliding the levers 36 inwardly.

The assembled hoisting head, casing, pallet and bricks are conveyed by the hoisting apparatus to a car or truck and lowered until the pallet rests thereon. The hoisting head is then released by grasping the handles 31 and pulling the reach rods 29 inwardly to rock the shafts 25 and swing the upper hooks 27 outward to release them from the keepers 9. The hoisting head may then be raised away from the casing, leaving the pallet, the bricks and the casing as a shipping unit. These shipping units may be stacked one upon another as shown in Fig. 7 with the pallet of the upper unit resting upon the protruding top of the lower stack to keep the weight from the lower casing 7. The casing protects the bricks during transportation by truck, car or boat. The bricks are particularly well prepared for shipment in freight cars. By packing them in caged units as described, the surging action, which sometimes rams out the ends of the car and damages the bricks, is practically eliminated. The cars can therefore be safely loaded practically to capacity. Consequently fewer cars are needed for a given quantity of bricks and the shipping cost is materially reduced.

The units may be unloaded from a car by another hoisting head precisely like the one described, and conveyed to a truck. When they reach their destination they may be again conveyed by such a head directly to the point where they are needed by the bricklayer. The bricks are thus spared an enormous amount of individual handling, and from the time they leave the brickyard until they reach the

delivery point they are protected from injury. They remain stacked and enclosed by the casing during all of the handling operation and during transportation, and are delivered unmarred.

When the bricks have been delivered and are to be removed from the pallet the casing 7 is removed from the stack. To release the casing from the pallet the levers 36 of the hoisting head are slid at their fulcrums to rock the large hooks 32 into operative engagement with the lugs 18 of the links 14. The levers 36 are then rocked to slide the hooks 32 upwardly and cause the lower hooks 12 to be rocked outwardly away from the keepers 6, as shown in Fig. 4. The upper hooks 27 remain in engagement with the keepers 9 so that the casing may be hoisted away from the stack, as shown in Fig. 5. The hoisting head is released from the removed casing by pulling the reach rods 29 inwardly to rock the shafts 25 and swing the hooks 27 free from the keepers 9, as shown in Fig. 6.

The bricks may be removed from a railway car and stacked as units in a retail yard. When this is done the enclosing cages may be left attached to the pallets to surround and protect the bricks or they may be removed and shipped back to the place of manufacture. When the bricks are taken as units from the retail yard for transportation to the job the casing may be placed around the bricks and attached to the pallet, if the original casing in which the bricks are shipped has been removed.

Whenever it is desirable to dump the bricks from the pallet and the enclosing cage into a truck it is only necessary to manipulate one of the levers 36 to release one set of hooks 12. This permits one end of the pallet to drop while the enclosing cage and the other end of the pallet is supported by the hoisting mechanism. This operation may be desirable at times and especially when the apparatus is used for handling ordinary bricks.

The operating means for making and breaking the lifting connections greatly facilitates the handling of the casing, the pallet and the stack units. Often a number of units are disposed close together, with insufficient clearance for a workman to get between them and connect or disconnect the casing and pallet. The present operating mechanism enables a workman located above and entirely clear of the casing and stack to easily operate all of the lifting connections for both pick-up and release.

In Fig. 9 is shown means to prevent an accidental release of the lower hooks 12 when the casing and pallet are unsuspended and there is no weight upon said hooks. Here the pin 16 of the link head 15 extends through slots 17^a each of which is formed adjacent its lower end with a lateral branch or notch 17^b. A leaf spring 43 is mounted within the chan-

nel iron, back of the slots and when the link head is shifted down to throw the hooks 12 into operative position, the spring engages the back of the link head and forces it outward to engage the pin in the slot extensions. This automatically locks the hooks in engagement with the keepers 6 and avoids all danger of an imperfect lifting connection when the pallet is hoisted. The link head may be readily unlocked to permit a release of the hooks by sliding the lever 36 for a rocking manipulation of the hook 32 to force the link head inwardly and disengage the pin 17 from the slot extensions 17^b.

While I have shown and described a practical and desirable form of my invention I do not wish to be limited strictly to this disclosure but reserve the right to make such structural changes as will lie within the scope of the claims.

What I claim is:

1. An apparatus for handling bricks comprising a pallet for supporting a stack of bricks; a cage to surround said stack; a hoisting head adapted to be suspended; grappling means carried by the cage for lifting the pallet; grappling means carried by the hoisting head for lifting the cage and thereby lifting the pallet; manually operable means carried by the hoisting head for operating the said grappling means carried by the cage; and manually operable means carried by the hoisting head for operating the said grappling means carried thereby.

2. An apparatus for handling bricks comprising a pallet for supporting a stack of bricks; a cage to surround said stack; a hoisting head adapted to be suspended; grappling means carried by the cage for lifting the pallet; grappling means carried by the hoisting head for lifting the cage and thereby lifting the pallet; manually operable means carried by the hoisting head for operating the said grappling means carried by the cage; and manually operable means carried by the hoisting head for operating the said grappling means carried thereby, the said grapple-operating means being operable from points adjacent the center of the hoisting head.

3. An apparatus for handling material comprising a pallet for supporting a load of material; a cage to surround said load; a hoisting head adapted to be suspended; a releasable lifting connection between the cage and pallet for lifting the latter with the cage; a releasable lifting connection between the hoisting head and the cage for lifting the pallet and the cage with the hoisting head; and manually operable means carried by the hoisting head for releasing said lifting connection between the cage and the pallet.

4. An apparatus for handling material comprising a pallet for supporting a load of material; a cage to surround said load; a

- hoisting head adapted to be suspended; a releasable lifting connection between the cage and pallet for lifting the latter with the cage; a releasable lifting connection between the hoisting head and the cage for lifting the pallet and cage with the hoisting head; manually operable means carried by the hoisting head for releasing said lifting connection between the cage and pallet; and manually operable means carried by the hoisting head to release said lifting connection between the head and the cage, both of said manually operable means being operable from points adjacent the center of the hoisting head. 5 70
5. An apparatus for handling bricks comprising a pallet for supporting a stack of bricks; a cage for surrounding said stack; a hoisting head adapted to be suspended; a pair of rock shafts carried by the hoisting head at opposite ends thereof; a plurality of lifting hooks fixed to each of said shafts to rock with them; keepers carried by said cage adapted to be engaged by said hooks to make releasable upper lifting connections between the hoisting head and cage; a pair of rock shafts mounted upon the cage at opposite ends thereof; a plurality of lifting hooks fixed to each of said cage shafts to rock with them; keepers carried by the pallet and adapted to be engaged by the latter hooks to make lower lifting connections between the cage and the pallet; manually operable means carried by the hoisting head to rock the shafts thereof for making and releasing said upper connections; and manually operable means carried by the hoisting head to rock the cage shafts for making and releasing said lower connections. 15 75
6. An apparatus for handling bricks comprising a pallet for supporting a stack of bricks; a cage for surrounding said stack; a hoisting head adapted to be suspended; a pair of rock shafts carried by the hoisting head at opposite ends thereof; a plurality of lifting hooks fixed to each of said shafts to rock with them; keepers carried by said cage adapted to be engaged by said hooks to make releasable upper lifting connections between the hoisting head and cage; a pair of rock shafts mounted upon the cage at opposite ends thereof; a plurality of lifting hooks fixed to each of said cage shafts to rock with them; keepers carried by the pallet and adapted to be engaged by the latter hooks to make lower lifting connections between the cage and the pallet; manually operable means carried by the hoisting head to rock the shafts thereof for making and releasing said upper connections; and manually operable means carried by the hoisting head to rock the cage shafts for making and releasing said lower connections. 20 80
8. An apparatus for handling bricks comprising a pallet for supporting a stack of bricks; a cage for surrounding said stack; a hoisting head adapted to be suspended; releasable lifting connections between said hoisting head and cage for lifting the latter; a pair of rock shafts mounted upon opposite ends of the cage; a plurality of lifting hooks fixed to each shaft to rotate with it; keepers upon the pallet to be engaged by said hooks for lifting the pallet; links connected to said shafts for rotating them, extending upward at the ends of the cage and slidably mounted at their upper ends; a pair of levers mounted upon the hoisting head at opposite sides of the center of the head to rock and slide at their fulcrums each lever having a manual operating arm directed inward toward the center of the hoisting head and another arm directed outward; a pair of links pivotally connected to the outer arms of said levers extending downward, pivotally and slidably connected to the hoisting head intermediate their ends and formed with hooks at their lower ends to rock into and out of operative connection with the upper sliding ends of the shaft-operating links upon the cage when the levers are slid at their fulcrums, and adapted to cause the rocking of the hooks when the levers are rocked. 25 85
9. An apparatus for handling bricks comprising a pallet for supporting a stack of bricks; a cage to surround said stack; a hoisting head adapted to be suspended; grappling means carried by the cage for lifting the pallet; automatic locking means to prevent accidental release of said grappling means; grappling means carried by the hoisting head for lifting the cage and thereby lifting the pallet; manually operable means carried by the hoisting head for releasing said locking means and operating the said grappling means carried by the cage; and manually operable means carried by the hoisting head for operating the said grappling means carried thereby. 30 90
10. An apparatus for handling bricks comprising a pallet for supporting a stack of bricks; a box-like cage open top and bottom and formed with solid side walls to surround 35 95

said stack and permit the top of the stack to protrude; a hoisting head adapted to be suspended; grappling means to detachably connect said hoisting head to the pallet for lifting the pallet, the bricks and the cage; and manually operable means carried by the hoist-head for engaging and disengaging said grappling means.

11. A hoisting and conveying apparatus comprising a pallet for supporting a load; a cage to surround said load; a hoisting head adapted to be suspended; releasable lifting connections between the cage and opposite ends of the pallet for lifting the latter with the cage; releasable lifting connections between the hoisting head and the cage for lifting the pallet and cage with the hoisting head; and manually operable means carried by the hoisting head for independently releasing said lifting connections at opposite ends of the cage and the pallet.

12. A hoisting and conveying apparatus comprising a hoisting head adapted to be suspended; a load support; devices carried by said head and spaced materially outward on opposite sides of its center to effect releasable lifting connections between the head and the opposite ends of said load support; and operating means for said devices extending inwardly therefrom toward the center of the head and adapted to be operated by an operator at said point for the independent operation of said devices at the opposite ends of the load support.

13. A hoisting and conveying apparatus comprising a hoisting head adapted to be suspended; devices carried by said head and spaced materially outward from its center to effect releasable lifting connections between the head and the load support; operating means for said devices extending inwardly therefrom toward the center of the head and adapted to be operated by an operator at said point for the independent operation of said devices; and means carried by the hoisting head to effect a lifting connection between the head and a cage for surrounding the load.

14. A hoisting and conveying apparatus comprising a pallet for supporting a load; a cage for surrounding the load upon the pallet; a hoisting head adapted to be suspended; releasable lifting connections between said head and cage; a pair of rock shafts mounted upon opposite ends of the cage; a plurality of hooks fixed to said shaft to rock with them; keepers carried by the pallet to be engaged by said hooks to make lifting connections; and manually operable means mounted upon the hoisting head to effect the independent rocking of said shafts from the hoisting head.

15. A hoisting and conveying apparatus comprising a pallet for supporting a load; a cage for surrounding the load upon the

pallet; a hoisting head adapted to be suspended; releasable lifting connections between said head and cage; a pair of rock shafts mounted upon opposite ends of the cage; a plurality of hooks fixed to said shafts to rock with them; keepers carried by the pallet to be engaged by said hooks to make lifting connections; and manually operable means mounted upon the hoisting head to effect the rocking of said shafts from the hoisting head.

16. A hoisting and conveying apparatus comprising a pallet for supporting a load; a frame to engage said load and retain it upon the pallet; a hoisting head adapted to be suspended; releasable lifting connections between said load-retaining frame and opposite ends of the pallet for lifting the latter with the frame; releasable lifting connections between the hoisting head and the frame for lifting the pallet and frame with the hoisting head; and manually operable means carried by the hoisting head for releasing said lifting connections between the frame and the pallet.

17. An apparatus for handling material comprising a pallet for supporting a stack of the material; a cage to surround said stack; a hoisting head adapted to be suspended; detachable connecting means between said hoisting head, the pallet and the cage; and manually operable means carried by the hoisting head for engaging and disengaging said connecting means.

18. An apparatus for handling material comprising a pallet for supporting a load of material; a cage to surround said load; means to detachably lock the cage to the pallet; a hoisting head adapted to be suspended; means connecting the said hoisting head to the pallet and the cage; and operating means carried by the hoisting head and manually operable from a point adjacent the center of the head to actuate the said connecting means.

19. An apparatus for handling material comprising a pallet for supporting a load of material; a cage to surround said load; means to detachably hold the cage to the pallet against lateral shifting movement on the pallet; a hoisting head adapted to be suspended; means connecting the said hoisting head to the pallet and the cage; and operating means carried by the hoisting head and manually operable from a point adjacent the center of the head to actuate the said connecting means.

In testimony whereof I hereunto affix my signature.

EDGAR T. JUDSON.
